(57) **CLAIM**

The ornamental design for a base of coffee capsule sealer as shown and described.

DESCRIPTION

FIG. 1 is a front, left and top perspective view of a base of coffee capsule sealer, showing my design.

FIG. 2 is a rear, right and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof; and,

FIG. 9 is another front, left and top perspective view of the base of coffee capsule sealer of FIG. 1, showing a combination with an unclaimed cover.

The broken lines depict environmental structure of the base of coffee capsule sealer that form no part of the claimed design.

1 Claim, 9 Drawing Sheets
